FOUNDATION SYSTEM FOR STRUCTURES

Manuel González Flores, Mexico City, Mexico

Application March 5, 1948, Serial No. 13,187
In Mexico March 5, 1947

3 Claims. (Cl. 61—50)

1

The present invention deals with a new method and apparatus for laying a foundation on piles for buildings. It differs from the known methods in the following: the load of the structure is transmitted to the piles by means of a special method of support. The latter makes it possible to change the support level of the beams of the foundation on the above mentioned piles and with it, the level of the building itself. This change may be made either total or partial, depending on what is desired. Also, this invention deals with special devices or jacks for the purpose of pulling out the wedges without diminishing in any degree the pressure upon the pile, also for ascertaining the relative movement between the ground and the building and finally, for the purpose of ascertaining the pressure exercised by the building upon the land and any part of the piles.

In order to realize the advantages of this new method of my invention, may I start with a description of the condition of the ground in general and in particular of the subsoil of the city of Mexico. The layers of the subsoil of this city have a water content which varies around 80% and due to the evaporation of the water, the ground compacts. As a result of this evaporation of the water in the ground the city sinks with respect to the surrounding hills at a rate of between 15 and 20 centimeters per annum. Experience has shown that the layers of soil from the level 0 down to 35 meters below, suffer a drying-up varying between 5-10 centimeters per annum.

In placing a load on the soil mentioned, the latter is partly supported, by the water contained in the soil and as a result, this water is expelled through the pores while at the same time the structure of the soil which becomes deformed or compacted by being reduced in volume, takes up this load. At the moment when the structure of the soil supports the entire load, no more water evaporates and the soil has suffered its maximum deformation. At that moment I might say, the ground has consolidated under the load of the building load and as a result of such consolidation, the ground is reduced in volume. For that reason the load which is on top of the soil descends or as we generally say in the case of buildings, it "sinks".

The consolidation of a given ground may be due to two reasons: (1) to a load being placed upon it which expels the water by pressure, or (2) by the removal of the water through some other means such as drainage, pumping, evaporation, etc.

Any rigid object which pierces the layers of the

2

soil, such as for example the tube of an artesian well or a pile, due to the drying up of the soil, will always stick out of the surface more and more as the water is removed from the soil. This seeming protrusion is greater the longer the rigid object is, and particularly if its deepest end is based on a hard sub-stratum.

The system of laying foundations on piles has come to be general in Mexico City, especially for massive structures. This method provides for a leveling of the heads of the piles. The ground is leveled and rammed in the spot where the foundation beam is supposed to rest and the latter is properly reinforced. In this manner the heads of the piles are actually submerged within the concrete of the beam or the latter remain supported in this manner first, on the ground and at the same time the piles. Shortly after, however, the piles appear to emerge from the ground which carries the structure on top of them, creating the effect of causing the building to rise and the surrounding soil to drop away within a short time. Thus, in case there does not exist any hydraulic pressure which might shoulder the burden of supporting the edifice, we cannot assume that the building would be supported in part by the ground and partly by the piles when actually it rests entirely on these piles, provided that the number of the piles laid down are sufficient to carry the entire weight of the building.

This phenomenon constantly causes expenditures in the way of repairs with regard to the building and considerable obligations to change and frequently level the sidewalks which surround a given building, as well as to repair water mains, sewers and gas. Also, it causes disputes with the owners of surrounding buildings as well as in many cases the payment of indemnities for damages caused by the cave-ins. In addition, by leaving the building solely and exclusively supported by the piles and completely separated from the ground, the stability of such building becomes endangered and there is on way of regulating same since the heads of the piles are embedded in the beam. Concrete examples from the history of Mexico City include the case of the Condesa pumping plant which up to date has emerged from the surrounding territory by about 1.50 meters. Or there is the Statue of Independence where it was necessary to re-arrange its entire circular platform and to construct isolated pieces in order to avoid a new fracture. Or there is the branch of the Bank of Mexico which actually rises some 10 centimeters per annum. These conditions are still more aggra-

vated by the fact that since the layer of soil on which the piles are supported, often suffers a consolidation itself, it is possible for some piles to sink at an uneven degree as compared to others, with the result that the building itself becomes inclined.

This same phenomenon may be observed in any well shaft of a depth exceeding 30 meters. If the pipe is of cast iron or of thick sheet metal, it will emerge from the surface by about 10 to 15 centimeters per annum.

For the reasons above stated, up to date the laying of foundations on piles has proved very unsuccessful in regions of clayey soil such as the city of Mexico.

My invention treats the foundation laying in such manner that the tops of the piles remain perfectly accessible, passing through the beams or between two brackets. Their support of the foundation rests on removable wedges and anchored pins. By means of the latter it is possible, simultaneously with the emergence of the piles, to lower the foundation and building at the same or lesser speed with respect to the surrounding ground. In this manner the building in question will not be detached from the surrounding ground and the building will be supported simultaneously by the ground and by the piles.

This method of control is so devised that this operation may be carried out either totally or partially, on one or on all the piles, depending on whether the emergence of the piles is uniform or that one or several behave different from the rest.

This method of my invention makes it possible to ascertain in a simple manner the load supported by any given pile or whether any of them or several are failing, as well as determine the relative movement between the piles and the ground.

Description

The details characteristic of my new system of laying a foundation for buildings on piles is shown clearly in the following descriptions as well as in the diagrams which are attached herewith for the purpose of illustrating the invention. In these diagrams the same symbols are used to indicate identical parts in all ten illustrations.

Figure 1 shows the plan of several foundation beams supported by a series of piles which run through the girders or brackets,

Figure 2 shows a section of a girder or bracket through which a pile runs. The head of the pile slightly penetrates the girder or bracket. From here up to the surface of the foundation the pile continues in a series of wedges or pile extensions and finally, at its uppermost point, in a saddle piece which transmits the weight supported by the pile to pins anchored in the foundation,

Figure 3 shows a section of a girder or bracket penetrated by a pile. This figure illustrates the case of the piles emerging with respect to the surrounding ground. In that case the building can continue to be fastened to the same ground, simply by unscrewing the nuts of the pins which support either part or the entire weight of the building,

Figure 4 shows a plan of the method by which the load (weight) of the building is transmitted to the piles,

Figure 5 shows a diagram of the method by which it is possible to remove the wedges without

diminishing in the slightest, the pressure exercised upon the piles,

Figure 6 shows the layout of the above attachment or special jack with all its components, with a part of the piece resting on the wedges removed,

Figure 7 shows a section of the beam or bracket passed through by a pile and its wedges, as well as the position which results when a wedge is removed, and the special jack has been withdrawn so that the frame rests on the next wedge,

Figure 8 shows in perspective, a wedge shaped like a step and this figure also shows the half rings (rims) which serve as packing for the step-like wedge,

Figure 9 shows the arrangement which serves in order to ascertain the relative movement between the ground and the building,

Figure 10 illustrates the method used to ascertain the pressure exercised by the building on the ground.

Figure 11 is a perspective of a jackarm.

In accordance with the method herein, we proceed with the laying of a foundation for a structure or building on a given ground, as follows:

We proceed to investigate the ground in the same manner and utilizing the same means as those now customarily used, establishing the head of every pile 1 on the corresponding level, in accordance with the number of wedges to be laid on top. In general this will be at the level of the ground.

Where the extreme top of every pile remains in an accessible place, there arises under certain conditions the necessity of using hollow piles, practically in their entire lengths. In this manner I make it possible for the pile to be filled with provisional metallic core which enables it to enter more easily and avoids any flexing. Also it makes possible its sinking by a method different from ramming.

Since the hollow part is free, it is possible by means of a rod or some other device, to know whether the pile remains straight, vertical and complete.

On top of each pile 1 is arranged a series of wedges or removable extensions 2 which altogether result in an elevation slightly higher than the beam through which they pass. This series of wedges is arranged in the interior of a tube or opening 3 in the beam which protects the same in passing through the beam and leaves them free to move vertically.

These wedges 2, according to Figure 8, have been given a special form, consisting of two bodies or cylinders *m* and *n* of which the upper one *m* has a smaller diameter than the lower one *n*. Generally, they are constructed in cylindrical form and are made of concrete or some other suitable material.

The pieces 5 are a number of half circles or crowns which lock up the wedges, fitting in with the steps of the upper part *m* of the wedges.

Parallel to the tubes or openings 3, there have been anchored to the beam, two or more pins with screws 6. These pins are capable of supporting a traction equal to the largest load which the pile is capable of supporting.

To these pins 6 is fastened by means of screws 7 the saddle 8 which, resting on the uppermost wedge 2 of the beam, transmits the entire load of the beam to the pile.

The general support or saddle 8 is equipped with openings for the pins 6 which are sufficiently

large in order to avoid damage to the thread of these screws whenever one is tightened more than the other. Between the screw 7 and the saddle 8 is arranged a piece 9 which has a globular base and permits the saddle 8 to rock without bending the screw and with it, pin 6.

As soon as each pile has been equipped with its wedges, tubes or special center pieces, and saddle frames, I proceed to install the beams and brackets of the foundation. In this manner the entire load is transmitted to the piles by means of the saddle 8, thus leaving the foundation suspended on these general supports.

In case the foundation happens to be located beneath the subsoil level, the water will have the tendency of coming between the wedges 2 and the beam. In order to avoid this, a stopper has been provided which will block this process. This stopper consists of a packing 10, a collar 11 insulated and fixed in the cement and between these two, a burr 12.

In case the foundation does not happen to be beneath the subsoil level, the necessity of avoiding the entry of water no longer exists.

Method for ascertaining the relative displacement or movement between ground and building

Whenever the piles begin to protrude as a result of the phenomena mentioned above and if as a result of this, the building begins to become separated from the surrounding soil, such movement may be easily ascertained by means of the difference in level between a fixed mark located in the ground and the structure of the building. However, the most practical means for this purpose has been provided by me in form of the device indicated in Figure 9. Here a tube 13 is anchored in the cement of the building. This tube protrudes from the building by a length exceeding the level of the subsoil water. Within this tube is provided a rod 14 marked equally with divisions and subdivisions. The lower end of this rod is anchored in a section 15 of concrete resting directly on the ground.

Whenever the structure supported by the piles begins to become separated from the ground, the rod 14 permits us to read off the length of this separation and, in accordance with these readings, the corresponding corrections of the piles can be made.

Method for ascertaining the load carried by each pile

Between the nuts 7 and the brackets or saddles 8 or, better still, between the uppermost wedge 2 and the overall frame, there may be installed pieces of metal with a low elasticity, i. e., which have very important deformations with respect to a low stress and nevertheless have a very high elastic limit. By means of an extensometer these deformations are measured and we then know the charge which they support and with it, the charge which is transmitted onto a given pile. Knowing this, we can of course, easily adjust the pile in question, augmenting or diminishing its pressure. By deducting from the total weight of the building the sum of the loads supported by the piles, we indirectly obtain the pressure which the building as such exercises or brings to bear upon the ground.

Method of ascertaining directly and checking the pressure exercised by the building on the soil

For the purpose of accomplishing the latter, I have designed a device illustrated in Figure 10.

The device consists of two plates whose perimeters are joined 16 and the interior of which is connected by a tube 17 which in turn projects into the building. This tube is filled with water, mercury or some other liquid which easily indicates the pressure in question. The plates 16 are contained in between a concrete beam of the structure and another plate which may be of concrete too, and which rests on the ground.

10 The pressure to which the enclosed receptacle is subjected may be easily read off by the height of the liquid in the tube 17 which in its upper portion is transparent.

Method of causing the structure to sink so as to make it rest permanently on the ground and the piles

Whenever the observation is made that the building is rising off the ground, say by 2 or 3

20 millimeters, the screws are loosened from all the piles. This operation should be made simultaneously or, better still, in small steps one by one. As soon as the speed of the movement has been ascertained or still better, data have been obtained of the pressure exercised by the foundation upon the ground and the piles, then the structure should be caused to descend before it rises or becomes separated off the ground, i. e., whenever it is noticed that the pressure upon a given piece of ground has lessened.

When the operation of the nuts 7 being loosened continues, then the rods 6 must be rather long and there often arrives the moment when the operation cannot be any longer continued, due 35 to the fact that the length of the rod has been used up. In order that the system herein may be used to its full capacity, it is necessary to allow for a descent up to one or two meters, since the drying up process of the ground in the city of Mexico assumes such proportions.

In order to succeed in such a descent of 1 or 2 meters I have provided the wedges 2 on top of each pile for the entire height of the foundation and even for a much lower descent of the general level, if so desired.

There are three chief methods of eliminating the wedges 2 in proportion to the rising piles:

(a) Considering the fact that it is possible to have the building always supported by the ground, the nuts 7 can be easily loosened from an individual pile in a degree sufficient for removing one of the wedges and then causing the saddle frame 8 to drop until it rests again on the next wedge. Whenever this is done the ground undergoes at that moment an overstress which, however, may be shortened to so brief a period that it is of no importance.

(b) When the total weight of the building is resting on the piles, additional piles may be put in the ground in such manner that, even if a wedge is left out from one pile without any special precaution, the remaining piles will easily support the additional weight.

In both cases mentioned steps should be taken 65 to the effect that the structure should be able to support the secondary forces caused by this operation.

(c) Finally, if it is thought undesirable to create additional stress on the ground, it is sufficient to make use of the device or jack for removal of the wedges as illustrated in Figures 5, 70 6 and 7.

This special jack, according to the illustrations, is composed of two or more pieces 18 which at their lower end are formed of two curved arms

extending right angularly from an upright piece. The upper end of each piece 18 has an opening through which a pin 19 extends. In turn, these pins extend through two arms of a second saddle 20 and at each end this saddle is provided with openings for insertion of the rods 6 and for securing same by means of the nuts 21.

In order to remove a wedge of a pile by means of this jack, the crown (rims) 5 of the second wedge are removed and in their places the beams are supported by means of the base of the jack pieces 18. These pieces 18 are secured to the upper saddle 20 by the pins 19. By means of the nuts 21 a pressure is brought to bear upon the second wedge. This pressure is equal or even larger than the one which was exerted on the saddle frame 8. Under these conditions the nuts 7 are loosened with the result that the saddle frame 8 comes loose and can be lifted, for the purpose of eliminating or removing the first wedge 2. After this wedge has been removed, the nuts 7 are tightened again until the saddle frame 8 rests with the same pressure as before on wedge No. 2 (see Figure 7). At this moment the jack which has served for removing the uppermost wedge may be removed, without the pressure on the pile being diminished.

By means of this method it is possible to modify the level for the building in any desired manner, without changing in any way the existing forces or pressures and even incline the building, if necessary.

The most suitable length of the rods 6, in view of dislodging the wedges, does not need to exceed a height of two or three of these wedges. As shown in Figure 8, these wedges have two levels and the load can be applied to any one of them and they are capable of supporting the entire load on any one of these two levels.

The crown 5 of the wedges 2 are good for two purposes: first, they aid in transmission of the load and second, they facilitate the keeping out of the water.

These wedges may be used either singly or joined to each other. However, if it is desired to give them additional strength, they can be joined together with mortar and a rod in such manner that this combination can be easily broken in order to remove the wedges.

Once the last of the wedges has been removed and there still exists the necessity of lowering the building, the operation may be continued by cutting down the pile to a shape paralleling that of the removed wedges, i. e., they can be cut up first into a crown and later into what would correspond to a wedge. In this case the operation of a temporary support would be carried out exactly in the same form as if the wedges were there.

It will be understood that the foregoing descriptive memorandum does not intend to limit my rights to this invention strictly to the letter of same nor much less to the illustrations herein, since it will be possible to effect some changes and modifications which, however, would in no way change the essence of this invention.

As a result of the foregoing, the wedges 2 may or may not consist of one piece as the samples in the illustrations or they might even be three and have two levels of such kind that, alternatingly, the center one or the two lateral ones could support the load of the pile whereupon the jack for the removal of the wedges

may be supported either by the side ones or the center one.

The wedges 2 may be circular, square or of any other geometric form and they may or may not be covered by a cover which would prevent still more the entry of water. When the wedges are removed, the water can drain off until the level of the water is lowered and the work can proceed under dry conditions.

10 The piles may be either massive or hollow, partly or entirely, and may consist of wood, cement or any other material and may be the same as the wedges.

15 The packing between the pile and the frame also may employ either a liquid or a granulated material and its evaporation may be controlled by means of a valve.

18 The frame may consist of one, two or more pieces, rectangular or of any other geometric form according to needs.

20 What I claim is:

1. The combination with a building structure having a foundation beam formed with vertical passageways therethrough, piles projected into the ground in alignment with said passageways, removable pile extension members disposed in superposed relation on the upper end of each pile and projecting upwardly through each passageway, and vertically adjustable means spanning each passageway secured to said beam and the upper one of said extensions for supporting the beam on the pile.

2. The combination with a building structure having a foundation beam formed with vertical passageways therethrough, piles projected into the ground in alignment with said passageways, removable pile extension members disposed in superposed relation on the upper end of each pile and projecting upwardly through each passageway, vertically adjustable means spanning each passageway secured to said beam and engaging the upper one of said extensions for supporting the beam on the pile, and means whereby the upper one of said extensions may be removed, said first named means including adjustable means whereby the beams may be lowered after removal of a pile extension.

3. The combination with a building structure having foundation beams formed with vertical passageways therethrough, piles projected into the ground in alignment with said passageways, removable pile extension members disposed in superposed relation on the upper end of each pile and projecting upwardly through each passageway, means spanning each passageway secured to a beam engaging the upper one of said extensions for supporting the beam on the pile, said means including upstanding threaded bolts fixed at their lower ends to said beams, a saddle loosely engaging pairs of said bolts and spanning an opening, and nuts threaded onto said bolts; adjustment of said nuts effecting vertical movement of the foundation relative to the piles.
